CONVERTIBLE HEATING ELEMENT

Clyde S. Simpelaar, Racine, Wis., assignor to
 Modine Manufacturing Company, Racine, Wis.,
 a corporation of Wisconsin

Application August 13, 1945, Serial No. 610,434

8 Claims. (Cl. 257—159)

1

This invention relates to a convertible heating element commonly used in connection with convection heaters, and its principal object is the provision of means to convert a heating element through which streams of fluid flow in parallel relation through several tubes, into a heating element in which the streams flow in series through the same tubes.

Another object is the provision of a heating element composed of several tubes connected to headers or tanks, with means associated with said headers or tanks whereby to cause fluid to flow through said tubes in series.

Another object is the provision of removable and replaceable sleeves in conjunction with the headers whereby the flow through the tubes may be converted from parallel streams to streams that flow in series through the several tubes.

With these and other objects and advantages in view, this invention consists in the several novel features of construction, arrangement and combination of parts hereinafter fully described and more particularly defined in the appended claims.

The invention is clearly illustrated in the drawings accompanying this specification, in which:

Fig. 1 is a view partly in plan and partly in horizontal section through a convertible heating element embodying a simple form of the invention, part of the heating element being broken away;

Fig. 2 is a view partly in side elevation and partly in vertical longitudinal section taken on the line 2—2 of Fig. 1;

Fig. 3 is a view partly in plan and partly in horizontal section of the heating element partly broken away, in which the flow converting means has been removed;

Fig. 4 is a central vertical section of a modified form of sleeve;

Fig. 5 is a view partly in plan and partly in horizontal section of a modified form of the invention;

Fig. 6 is a vertical section taken on the line 6—6 of Fig. 5;

Fig. 7 is a view partly in plan and partly in horizontal section of a second modification;

Fig. 8 is a vertical section taken on the line 8—8 of Fig. 7; and

Fig. 9 is a perspective view of the sleeve employed in the inlet header of the modified form shown in Figs. 7 and 8.

Referring to said drawing, and first to Figs. 1 to 4 inclusive, the reference character 10 designates an inlet header, and 11 an outlet header of a convertible heating element employing a

2

simple embodiment of the present invention. Each header contains a cylindrical chamber 12, the walls of which are threaded at one end for the reception of supply and discharge pipes, respectively, indicated by 13—14. These walls are also threaded at the other end for the reception of plugs indicated respectively at 15—16.

Connecting the headers are fluid conducting tubes 17, 18, 19 on which are strung fins 20 as is customary. The tubes extend in parallel relation with each other, with the tube 17 extending between oppositely disposed ports 21, 21a in the walls of the headers, and the tubes 18, 19 being disposed laterally of the headers and being formed with elbow bends 22, 23 at their ends, which elbow bends enter ports 24, 25, 26, 27 formed in the walls of the headers, two ports of each header being disposed diametrically opposite each other and at 90 degrees apart from the ports 21, 21a, respectively. The tubes may be brazed to the headers or secured thereto in any other approved manner.

Removably and replaceably held in the headers are sleeves 28, 29 for converting a heating element from one in which the flow from the inlet header to the outlet header is through parallel paths, into a heating element in which the flow from the inlet header to the outlet header is in series through said tubes.

When the heating element is used without the sleeves 28, 29, the flow of the heating medium is along parallel paths as indicated by the arrows in Fig. 3.

To convert the heating element into one in which the flow of the heating medium is through the tubes in series, the sleeves 28, 29 are employed. These sleeves may be formed integrally with the plugs or they may be welded thereto or they may be made separate therefrom, whichever is found most desirable. When made separate from the plugs the sleeves, one of which is seen in Fig. 4 at 28a, may be secured in the headers by a driving fit, or they may be pinned or keyed thereto. The sleeves are formed with ports to direct the heating medium through the tubes so as to flow therethrough in series. The sleeve 28 is formed with ports 39, 30, 31 which register with the ports 21, 24 and 25, respectively, and the port 39 establishes a communication between the interior of the sleeve 28 and the tube 17. A by-pass or passageway, such as a tube 32, connects the ports 30, 31 and establishes communication between the tubes 18 and 19.

The sleeve 29 is formed with ports 33, 34, 35 which register respectively with the ports 21a, 26

and 27 of the outlet header, and a by-pass or passageway, such as an elbow tube 36, is provided between the ports 33 and 34, which elbow tube establishes communication between the tubes 17 and 18. The port 35 establishes communication between the tube 19 and the interior of the sleeve 29.

When the heating element is equipped with the sleeves, the flow through the tubes is in series as indicated by the arrows in Fig. 1. The heating medium then enters the inlet header from the supply pipe 13, flows through the ports 39, 21 into and through the tube 17, thence through the ports 21a, 33 and through the elbow 36 and through the ports 34, 26 to and through the tube 18, and thence through the ports 24, 30, tube 32, ports 31, 25, to and through the tube 19, and thence through the ports 27, 35 into the interior of the sleeve 29, and out through the outlet pipe 14.

When the sleeves are omitted from the headers, the heating fluid enters the inlet header as above described, then flows through the several tubes in parallel streams (see Fig. 3) to and through the outlet header and discharges through the outlet pipe. This form of heating element is used principally when steam is employed as the heating medium, and the series flow heating element is employed when hot water is employed as the heating medium.

While the inlet and outlet pipes are shown as entering the headers at the lower ends thereof, they may enter the upper ends of the headers and the plugs are then used at the lower ends of the headers to close the open ends thereof.

In the modified form of the invention illustrated in Figs. 5 and 6 the headers 10a, 11a may be of the same form and construction as the headers of the form of the invention previously described. In this case the inlet pipe 13a enters the header 10a at its upper end and the discharge pipe 14a enters the header at its lower end. Two or more tubes 7a, 7aa, 22a, 23a enter the side walls of the two headers and connect them.

In the header 10a is secured a sleeve 28a having ports 39a which register with adjacent ends of the tubes 7a, 7aa, said sleeve having also ports 30a, 31a which register with adjacent ends of the tubes 22a, 23a. A cross wall or partition 28x extends through the sleeve from a point above the ports 39a to the opposite side of the sleeve at a point below the ports 30a, 31a, thereby dividing the sleeve into two unconnected chambers or passageways 40, 41. The inlet pipe 13a opens to the chamber or passageway 40 and the discharge pipe 14a opens from the chamber or passageway 41.

In the header 11a is secured a sleeve 29a which is formed with or provided with elbows 36a, 36aa which respectively connect the adjacent ends of the tubes 22a and 7a and the adjacent ends of the tubes 7aa, 23a.

With the sleeves present in the headers the flow of the fluid is from the chamber or passageway 40 through the two tubes 22a, 23a, through the elbows 36a, 36aa and back to the header 10a, through the tubes 7a, 7aa and into the chamber or passageway 41 and out through the discharge pipe 14a, the flow being through two sets of series connected tubes as shown by the arrows in Figs. 5 and 6.

To convert the heating element into a parallel flow element the sleeves are omitted. The flow through all of the tubes is then in one direction from the inlet header to the outlet header. The discharge pipe 14a is omitted from the header 10a, screwed into one end of the header 11a; a

plug similar to the plug 15 is screwed into the open end of the header 10a and a similar plug is screwed into the open end of the header 11a.

In the modified form of the invention illustrated in Figs. 7 to 9 inclusive, the headers, tubes and sleeve 28a may take the same form and arrangement as in the modified form seen in Figs. 5 and 6, but the sleeve 28b in the header 10a is of a different construction and provides for a series flow of the fluid through the several tubes as shown by the arrows in Fig. 7.

The sleeve is divided by three radially extending walls or partitions 28z into three chambers or passageways 40a, 40b, 41a which communicate respectively with the tubes 22a, 7a, 7aa and 23a. The top of the sleeve 28b over the chamber or passageway 40a is open whereby the fluid may enter the chamber or passageway 40a from the inlet pipe which is screwed into the upper end of the header 10a. The other two chambers or passageways 40b, 41a are closed at their upper ends by a wall 42 and the lower ends of the chambers or passageways 40a, 40b are closed by a wall 43. The lower end of the chamber or passageway 41a is open whereby the fluid may discharge through the discharge pipe which is screwed into the lower end of the header 10a.

To convert this second modified form of the invention into a parallel flow element, the sleeves 30 are omitted from the headers 10a, 11b, the discharge pipe 14a is omitted and screwed into one end of the header 11b, and plugs 15 are screwed into the open ends of both headers.

The flow is then from the inlet pipe into the header 10a and through all of the tubes, into the header 11b, from which it discharges through the discharge pipe.

It will be seen, therefore, that the header 10a in each modified form of the invention serves as an inlet header and outlet header when the sleeves are used for causing series flow in the tubes. Obviously fins may be applied to the tubes as in the first form described.

From the above it is apparent that I have provided a heating element which may be readily converted from a parallel flow heating element to a series flow heating element.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A heating element comprising an inlet header and an outlet header connected by several fluid conducting tubes, one of the tubes extending in a straight line from header to header and the other tubes each having bent elbow portions opening to the interior of the headers in a direction at right angles to the first mentioned tube, removable and replaceable sleeves one in each header, each of said sleeves having ports opening to the tubes connected to the header in which the sleeve is used, one of the sleeves having a by-pass therein extending diametrically thereacross and communicating with the tubes having the bent elbow ends and the other sleeve having a passageway therein in communication with the straight tube and one of the tubes having the bent elbow ends, said sleeves providing a series flow heating element, a supply pipe connected

to the inlet header and a return pipe connected to the outlet header.

2. In a heat exchanger, a header member having a cylindrical bore therein, a plurality of tubes having their corresponding ends secured to the header member and individually communicating with the bore therein, the axes of said ends of the tubes extending substantially radially with respect to the axis of said bore, and circumferentially spaced around the latter, and a sleeve removably positioned in said bore and having its outer side wall complementary to and engaging the side wall of said bore in fixed relation to the latter, said sleeve defining a fluid port for the heat exchanger communicating said bore with certain of said tubes and having a partition wall therein extending between circumferentially spaced tube ends, and providing a passageway between said tubes, said partition wall sealing said connected tube ends from other of said tube ends and from the fluid port defined by said sleeve.

3. In a heat exchanger, a pair of spaced header members, each having a cylindrical bore therein, a plurality of tubes extending between and having their corresponding ends secured to the respective header members and individually communicating with the respective bores therein whereby the tubes are connected in parallel therebetween, the axes of the corresponding ends of the tubes extending substantially radially with respect to the axes of the respective bores and circumferentially spaced around the latter, and a pair of sleeves, each of which is removably positioned in a respective bore and has its outer side wall complementary to and engaging the side wall of such bore in fixed relation to the latter, said sleeves defining the fluid inlet and outlet for the heat exchanger and communicating said bore with certain of said tubes and having partition walls therein extending between circumferentially spaced tube ends, and providing a passageway between said tubes, said partition wall sealing said connected tube ends from one another whereby the fluid flow from the inlet to the outlet through certain of said tubes is in series with the fluid flow in the rest of said tubes.

4. In a heat exchanger, a header member having a cylindrical bore therein, three tubes having their corresponding ends secured to the header member and individually communicating with the bore therein, the axes of said ends of the tubes extending substantially radially with respect to the axis of said bore, and circumferentially spaced around the latter, and a sleeve removably positioned in said bore and having its outer side wall complementary to and engaging the side wall of said bore in fixed relation to the latter, said sleeve defining a fluid port for the heat exchanger communicating said bore with one of said tubes and having a partition tube therein extending between the other spaced tube ends, and providing a passageway between the latter tubes, said partition tube sealing said connected tube ends from the other tube end and from the fluid port defined by said sleeve.

5. In a heat exchanger, a header member having a cylindrical bore therein, two pairs of tubes having their corresponding ends secured to the header member and individually communicating with the bore therein, the axes of said ends of the tubes extending substantially radially with respect to the axis of said bore, and circumferentially spaced around the latter, and a sleeve removably positioned in said bore and having its

outer side wall complementary to and engaging the side wall of said bore in fixed relation to the latter, each end of said sleeve defining a respective fluid port for the heat exchanger communicating one end of said bore with one pair of said tubes and the other end of said bore with the other pair of tubes, said sleeve having a partition wall therein extending between circumferentially spaced tube ends, and providing passageways between the respective tubes of each pair, said partition wall sealing the tube ends of one pair and the port associated therewith from the other pair of said tube ends and the fluid port associated with the latter.

15 6. In a heat exchanger, a header member having a cylindrical bore therein, two pairs of tubes having their corresponding ends secured to the header member and individually communicating with the bore therein, the axes of said ends of the tubes extending substantially radially with respect to the axis of said bore, and circumferentially spaced around the latter, and a sleeve removably positioned in said bore and having its outer side wall complementary to and engaging the side wall of said bore in fixed relation to the latter, each end of said sleeve defining a respective fluid port for the heat exchanger communicating one end of said bore with one of said tubes and the other end of said bore with another of said tubes, said sleeve having a partition wall therein extending between the remaining tube ends, and providing a passageway between the latter tubes, said partition wall sealing the respective fluid ports and tube ends associated therewith from each other and from said connected tube ends.

20 7. In a heat exchanger, a pair of spaced header members, each having a cylindrical bore therein, two pairs of tubes extending between and having their corresponding ends secured to the respective header members and individually communicating with the respective bores therein whereby the tubes are connected in parallel therebetween, the axes of the corresponding ends of the tubes extending substantially radially with respect to the axes of the respective bores and circumferentially spaced around the latter, and a pair of sleeves, each of which is removably positioned in a respective bore and has its outer side wall complementary to and engaging the side wall of such bore in fixed relation to the latter, one of said sleeves defining the fluid inlet and outlet for the heat exchanger and communicating one end of the associated bore with one pair of said tubes and the other end of said bore with the other pair of tubes, said sleeve having a partition wall therein extending between circumferentially spaced tube ends, and providing passageways between the respective tubes of each pair, said partition wall sealing the tube ends of one pair and port associated therewith from the tube ends of the other pair and port associated with the latter, the other sleeve having partition walls therein connecting each of the respective tubes of one pair with a respective tube of the other pair whereby the fluid flow from the inlet to the outlet through certain of said tubes is in series with the fluid flow in the rest of said tubes.

25 8. In a heat exchanger, a pair of spaced header members, each having a cylindrical bore therein, two pairs of tubes extending between and having their corresponding ends secured to the respective header members and individually communicating with the respective bores therein whereby the tubes are connected in parallel

therebetween, the axes of the corresponding ends of the tubes extending substantially radially with respect to the axes of the respective bores and circumferentially spaced around the latter, and a pair of sleeves, each of which is removably positioned in a respective bore and has its outer side wall complementary to and engaging the side wall of such bore in fixed relation to the latter, one of said sleeves defining the fluid inlet and outlet for the heat exchanger and communicating one end of the associated bore with one of said tubes and the other end of said bore with another of said tubes, said sleeve having partition walls therein extending between the remaining tube ends, and providing a passageway between the latter pair of tubes, said partition walls sealing the respective fluid ports and tube ends associated therewith from each other and from said connected tube ends, the other sleeve having partition walls therein connecting the adja-

cent ends of each of said first-mentioned tubes with a respective tube end of said pair whereby the fluid flow from the inlet to the outlet through said tubes is in series.
